(57) **CLAIM**

The ornamental design for a precision real-time laser measurement and marking apparatus, as shown.

DESCRIPTION

FIG. 1 is a perspective view of a precision real-time laser measurement and marking apparatus showing my new design;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is another perspective view thereof; and,

FIG. 9 is another perspective view thereof.

The broken lines illustrate portions of the precision real-time laser measurement and marking apparatus or environmental structure that do not form a part of the claimed design.
